ERVING D. CLARK, OF SYRACUSE, NEW YORK.

MEANS FOR CONVERTING KEROSENE-OIL INTO EXPLOSIVE GAS FOR INTERNAL-COMBUSTION ENGINES.

1,211,087.

Specification of Letters Patent. Patented Jan. 2, 1917.

Application filed March 13, 1916. Serial No. 83,966.

To all whom it may concern:

Be it known that I, ERVING D. CLARK, a citizen of the United States, residing at Syracuse, in the county of Onondaga and State of New York, have invented certain new and useful Improvements in Means for Converting Kerosene-Oil into Explosive Gas for Internal-Combustion Engines, of which the following is a specification.

10 This invention relates to improvements in means for converting kerosene and other heavy oils into explosive mixtures for internal combustion engines, and has for its object to provide a novel, simple and inexpensive mechanism for attachment to any of the well-known types of engines, whereby the common kerosene or coal-oil used for illuminating purposes may be converted into an effective explosive mixture for driving the engines.

A further object is to provide novel and simple means comprising a number of chambers which are associated with the exhaust manifold for preheating a relatively large volume of air to be supplied to the carbureter at a temperature sufficiently high to absorb and vaporize the kerosene oil supplied by the carbureter.

30 A further object is to provide an electric heating coil which is disposed between the air chambers and the carbureter for initially heating the air for starting the engine when the latter is cold. And a further object is to provide means for injecting "priming" charges of the fuel into one or more of the air passages ahead of the carbureter and upon the heating coil for generating hot gas for starting the engine after intervals of idleness and for continuing the operation 40 of the engine until the exhaust manifold becomes hot enough to suitably heat the air in the chambers.

The various features and parts of the invention will be understood from the detailed 45 description which follows, and by reference to the accompanying drawing, in which—

Figure 1 is a side elevation and partial section, the section taken on line 1—1 of Fig. 2. Fig. 2 is a transverse vertical section substantially on line 2—2 of Fig. 1; certain parts being in elevation.

In the drawing, 2 represents the several cylinders of one type of internal combustion engine, to which my invention is shown

applied, each having intake ports 3 and exhaust ports 4.

55 My improvement is intended for attachment, with a few necessary changes, to all types of gas engines, and consists of the following parts or mechanism: 5 represents the exhaust manifold, which connects by suitable branches 6 to the several ports 4, the discharge of the exhaust taking place at 7. Through the center of the manifold 5 I dispose an air pipe or chambered part 8, which is open at one end 8' for the admission of air.

9 represents a casing or shell, either cast or otherwise fitted around the exhaust manifold 5, for providing a second air chamber, 70 extending substantially the length of the manifold. The corresponding end 9' of chamber or casing 9 is also open for the admission of air. The air drawn from the atmosphere into the chambers 8 and 9 is 75 heated by the exhaust and thence passes downwardly through pipes or passages 10 and 11, which connect respectively with the closed ends of the chambers, and then discharge the hot-air into a common conductor or receiving chamber 12, from which the hot air passes into an L-shaped part 13, which is connected to or forms a part of a carbureter.

80 The carbureter herein shown, consists of an annular tank or body 14, which contains the fuel-oil, preferably kerosene which is fed through a pipe 15. Within the body or tank 14 is the usual float 16, which controls the flow or feed of the oil to a needle-valve 85 tube or nozzle 17 through transverse passages 18. The top-end of the tube 17 is in the form of a shallow cup 17', which receives the successive charges of the oil 19 from the annular chamber 14'. The tube 17 90 extends downwardly through a central passage or opening 20 in the tank 14, and through and below the L 13, and its lower-end is threaded internally. 21 represents the needle-valve, having a stem 22, which 95 extends downwardly through the tube 17, its lower end being threaded for adjustment, and having a handle 23 for manipulating the valve. The lower end of the chamber 20, which may form one arm of the L 100 13, receives the hot-air from the pipe or chamber 12. The hot-air thence passes or is drawn upwardly by the suction of the en-

gine, and discharges into the gas-intake manifold 25, having branches 26 and 26' for connection with the several cylinders 2. A throttle 27 of the usual form is disposed 5 in the upper portion of the passage 20 just above the fuel cup 17'.

I have described with some particularity the carbureter shown in the drawing, but I do not wish to be limited to any special 10 type of mechanism.

To start the engine after an interval of idleness, when everything is cold, I provide an electric coil 28 of relatively high resistance wire, and dispose said coil in the chamber or passage 12, preferably directly beneath the lower end of the air pipe 11, the pipe 12 being lined with mica 12' to prevent short circuiting. The ends of the wire 28 pass upwardly through insulators 29, which 15 pierce the pipe 12, and connect with an electric battery (not shown). When the current is switched on to the coil 28, the latter instantly becomes red-hot, and heats the air in the pipe 12, before it is drawn into the 20 carbureter. To generate the gas for the preliminary charges, a small quantity of "priming" fluid, preferably consisting of a mixture of kerosene and gasolene, obtained from a small tank 30, which may be mounted on 25 the inside of the dash of an automobile, or at any other convenient place. The "priming" mixture is preferably carried to the pipe 11 by a pipe 31, one end of which connects with the tank 30, while the opposite 30 site end enters the pipe 11. A valve 32 may be located at or near the tank 30 for controlling the "priming" fluid. The oil from tank 30 is dropped upon the hot coil 28, which instantly vaporizes the oil, 35 and the latter is then absorbed by the hot air and sucked through the passage 20 and intake manifold 25 into the cylinders 2 where it is exploded. After the engine has 40 operated a few strokes, the exhaust manifold 45 becomes sufficiently hot to heat the air in the chambers or pipes 8 and 9 without the aid of the coil 28, and the current may then be turned off. As soon as the air in chambers 8 and 9, pipes 10, 11 and 12 is raised to 50 the proper temperature, the kerosene oil supplied by the carbureter and exposed in the cup 17' becomes absorbed by the pre-heated air as the latter is sucked upwardly through the chamber 20, and an effective explosive gas is formed for driving the engine. 55

Kerosene oil is much less volatile than gasolene or naphtha, and when the kerosene oil wells-up in the cup 17', unlike gasolene which almost instantly vaporizes, the kerosene oil scarcely vaporizes at all. But when the hot-air, as described, passes through the carbureter, completely enveloping the needle-valve and cup 17', it absorbs the kerosene and instantly forms a highly explosive mixture which drives the engine. The kero-

sene oil is richer in hydrocarbon than gasolene and when properly carbureted or vaporized through the absorption of the oil by the hot-air yields more power than the gasolene fuel in common use. Owing to the 70 lower volatilization of the kerosene and the distillates, a relatively large volume of the preheated air is required to effect the perfect vaporization of the kerosene, while good gasolene mixture may be produced by air at 75 normal temperatures. In practice I heat the air which is drawn through the chambers 8 and 9 to a temperature above 150° or 160° Fahrenheit, and when so heated the air readily absorbs the relatively small quantity 80 of the kerosene oil held by the cup 17'. This absorption of the kerosene by the hot-air, together with the strong and rapid inhalations of the engine converts the relatively heavy fuel into the finest atoms or vapor, 85 which readily ignites and burns without perceptible odor or smoke. For converting the kerosene, the volume of hot-air must be many times greater than is required for gasolene. This feature will be readily apparent 90 by reference to the drawing, which shows the relatively large and free passages 12 and 20. The only regulative feature I employ is the throttle 27, which alone may restrict or reduce the volume of the mixture or gas 95 which may be sucked into the engine. But the throttle does not restrict the proportions of the air and the fuel.

It is essential in carrying out my invention that the temperature of the air be considerably in excess of that usually employed in connection with gasolene and other light or more volatile fuel oils. I find that when cold or only slightly heated air is supplied to the carbureter, it yields a poor mixture 100 and consequently little power. By utilizing the hot exhaust manifold, as herein shown and described, I am able to obtain hot-air in suitable volume in a simple manner without extra expense, and except when the cold 105 engine is first started this hot-air supply is continuous and abundant. The chambers 8 and 9 are always open to the atmosphere, and as fresh air is constantly being drawn into said chambers by the suction of the engine, there is no danger of the air supplied 110 to the carbureter being overheated.

Having thus described my invention, what I claim as new and desire to secure by Letters Patent, is—

1. The combination with a conduit for the passage of a heating element having a plurality of independent chambers for conducting air to be heated by the heating element, a receiving means communicating 125 with all of said hot air chambers, means for feeding a priming fluid to one of the hot air chambers, a heating coil for vaporizing the priming fluid, and a carbureter communicating with the receiving means. 130

2. The combination with a conduit for the passage of a heating element, of an air conducting means for conveying air to be heated by the heating element, means dis-
5 charging a priming fluid in the air conducting means, a heating coil for vaporizing said priming fluid, and a conducting pipe for delivering said vaporized priming fluid and the heated air to a carbureter, substantially
10 as described. 25
3. The combination of a conduit for the passage of a heating element having an air chamber passing through its center, an independent air chamber enveloping the same,
- the corresponding ends of said chambers being open to receive incoming air to be heated by the heating element passing through the conduit, a receiving chamber common to both of said hot air chambers, a priming nozzle in one of said hot air chambers, a heating chamber at a point where the priming chamber communicates therewith for initially vaporizing the priming fluid, a carbureter, and means connecting the receiving chamber with the carbureter.

In testimony whereof I affix my signature.

ERVING D. CLARK.
